FIRING PIN ARRANGEMENT FOR GUNS

Reginald W. Hoagland, Washington, D. C., and
Charles M. Shepherd, Cottage City, Md., assign-
ors to Automatic Guns, Incorporated, Wash-
ington, D. C., a corporation of Delaware

Application June 20, 1936, Serial No. 86,423

12 Claims. (Cl. 42—69)

The present invention relates to a firing pin arrangement for automatic guns, and aims to provide a novel and improved association of elements for controlling operation of the firing pin, said firing pin being of the spring propelled type.

Another object of the invention is the provision of a pair of sears for catching the head of the firing pin and holding the same against forward movement during the final closing of the breech mechanism, one of said sears being manually controlled by a trigger for disengaging the firing pin head and releasing the spring propelled firing pin, while the other of said sears is disengaged by the complete locking of the breech mechanism in closed position.

Another object is to provide an element movable with the lock of the breech mechanism for blocking out the firing pin so as not to engage the primer of the cartridge should the breech mechanism not be completely locked, and for retracting the point of the firing pin from the indentation in the primer during the unlocking of the breech mechanism prior to ejecting the cartridge case from the gun.

A further object of the invention is to arrange the means for manually releasing the firing pin with the back plate of the receiver of the gun for preventing operation of said manual means when said back plate is partially or fully removed.

A still further object is to construct a head of a firing pin with a sear catching portion oppositely arranged from a bearing portion for preventing bending or flexing of the firing pin shank when said firing pin is retracted by engagement with a sear.

Another object is the provision of a movable member adapted to be moved in the course of movement of the trigger element for preventing accidental operation of the trigger.

It is also an object of the invention to provide various control means of the character indicated for a firing pin of an automatic gun, which are simple and substantial in construction, which may be manufactured economically, and which will be very efficient in use.

With the foregoing and other objects in view which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Fig. 1 is a fragmentary longitudinal section through the receiver of an automatic gun, showing the firing pin in position to be released, 5

Fig. 2 is a similar view showing the breech mechanism in its rear position, with the firing pin controlling element in position for automatic firing.

Fig. 3 is a section on line 3—3 of Fig. 1, looking down on the breech mechanism and the sears, 10

Fig. 4 is a cross-section on line 4—4 of Fig. 1, and

Fig. 5 is a section on line 5—5 of Fig. 1. 15

Referring to the drawings, the numeral 10 indicates a receiver, having opposite side walls 11 and a top portion 12, with a feed opening 13 therein. A guide rail 14 is carried by each side wall on which is reciprocatedly mounted a 20 bolt 15 of the breech mechanism, said bolt carrying a vertical movable lock 16 adapted to be raised and lowered by an actuating member 17, also arranged to reciprocate in the receiver.

Attached to the forward end of the receiver 25 10 is a barrel 18, while at the rear of said receiver is a removable back plate 19 slidably carried by the side walls 11 thereof and adapted to be lifted upwardly when removing.

In carrying out the invention, the bolt 15 30 has a longitudinal bore 20 therein, extending from the rear end thereof to a reduced portion 21 at the forward end of the bolt 15. Positioned in the bore 20 is a firing pin 22 having a reduced forward primer contact portion 23, which 35 slides in the reduced portion 21 of the bore. Threaded in the rear end of the bore 20 and positioned about the body portion of the firing pin 22, is a sleeve 24 against which the rear end of a coil spring 25 engages. The forward 40 end of the coil spring 25 abuts against a collar 26 on the firing pin adjacent its forward end.

On the rear end of said portion 22 of the firing pin is secured the forward end of an extension 27 of the head portion 28 of the firing pin. The extension portion 27 slides within the sleeve 24 while the head portion 28 is positioned to the rear of the bolt 15. At each side and at the rear of the firing pin head 28 are arranged a pair of rearwardly extending ears 29, each pair carrying a roller 30 which rides upon the upper surface of a rail 14. At the upper portion of the head 28 the forward face is angled slightly forward to provide a catch portion 31, which is adapted to be engaged for controlling move- 55

ment of the firing pin with respect to the bolt 15. The forward face of the firing pin head 28 is off-set so that the lower portion of said face is forward of the upper portion, said off-set 5 faces being connected by an angle-faced portion 32. These faced portions correspond to rear faced portions or a pair of ears 33 carried by the lock 16 and extending upwardly therefrom; the face portions of the ears 33 are 10 connected by an angle-faced portion 34. With this arrangement it is necessary for the lock 16 to be in its uppermost locked position and the various forward faced portions of the head 28 and various rear faced portions of the ears 33 15 meshed in order that the firing pin will protrude beyond the face of the bolt to fire a cartridge arranged in the chamber of the barrel. The ears 33 of the lock 16 straddle the extension portion 27 of the head 28.

20 Centrally of the receiver between the opposite side walls 11 thereof, and in the upper portion 12 is a longitudinal groove or recess 35, said recess or groove extending upwardly from the under side of the portion 12. A pivot pin 36 25 extends across the portion 12 of the receiver, and through the recess 35, and has mounted thereon for swinging movement a pair of sears 37 and 38. Both of the sears 37 and 38 extend forwardly from the pivot pin 36 and have catches 30 39 and 40, respectively, thereon. A spring 41 is positioned between each of the sears 37 and 38 and the top of the recess or groove 35 for holding said sears yieldably in their lowermost 35 positions.

35 On the forward end of the sear 37 is an extension 42 which engages an off-set portion or lug 43 at the forward end of the recess 35 for limiting downward movement of the sear 37. The extension 42 is adapted to be engaged by 40 one of the ears 33 of the lock for raising the sear against tension of the spring 41, the purpose of which will be set forth as the description proceeds.

The sear 38 has a rearward extension 44 45 thereon, which is provided with a slot 45 therein, through which extends a pin 46 carried by a U-shaped member 47 also arranged in the groove or recess 35 and having its opposite parallel portion at opposite sides of the extension 44. The slot 45 in the extension 44 has the lower face 50 thereof at the forward end thereof enlarged, as at 48, so that when the U-shaped member is moved forwardly in the groove or recess 35 and the pin 46 carried thereby is positioned in 55 the forward end of the slot 45, the sear 38 will be permitted to swing downwardly and engage the head of the firing pin by means of the coil spring 41.

On the upper portion 12 of the receiver 60 adjacent its rear end is attached by means of screws, rivets or the like, 49, a housing 50, having a slot 51 therein into which is positioned a trigger element 52 for forward and rearward sliding movement. The trigger element 52 has 65 a forwardly extending portion 53 and a rearwardly extending portion 54 which overlap an opening extending between the recess 35 and the slot 51. Through the opening extends a depending lug 55 of the trigger element, which 70 has attached thereto the rear end of a rod 56, the forward end of the rod 56 being connected to the U-shaped member 47. A pair of lugs extend downwardly from the top portion 12 of the receiver at opposite sides of the rod 56 and provide an abutment for the rear end of a coil spring 75

57 arranged about the rod 56 and has its forward end bearing against the U-shaped member 47 for normally holding said U-shaped member and trigger element in their forward position. The trigger element 52 has an upstanding ear 58 5 provided with an eye therein to which a cord or cable 59 is attached. Mounted on the housing 50 is a roller 60 under which the cable or cord 59 passes, causing the trigger element to be pulled rearwardly independent of the line of pull on the cable or cord 59.

Pivoted in the rear portion of the slot 51 in the housing 50, as at 61, is a bar 62; the rear end of the bar 62 is engaged by an extension 63 on the back plate which holds the rear end of the bar 62 down against tension of a spring 64, thus holding the forward end of the bar 62 out of the path of movement of the trigger element 52. However, should the rear plate be slid upwardly for removal, the spring 64 would cause 20 the forward end of the bar 62 to move down and thus prevent the trigger element from being moved rearwardly.

The housing 50 has an extension 65 to one side thereof that is grooved from the under side to 25 provide an opening 66 to communicate with the slot 51 in the housing. Slidably arranged in the opening 66 is one portion 67 of an L-shaped member 68. The other portion of said L-shaped member extends upwardly and provides a hand-engaging portion 69. From the under side of the L-shaped member and extending into the portion having the hand-engaging portion 69 30 thereon, is an opening 70 in which is arranged a coil spring 71 which applies pressure on a 35 ball 72. In the upper surface of the receiver over which the L-shaped member slides is a pair of small pockets 73 into which the ball 72 engages for holding the slidable L-shaped member in either operative or inoperative position. 40 A screw 74 is threaded into the receiver for forming a stop to limit outward sliding movement of the L-shaped member. When the L-shaped member is moved to its innermost position, the portion 67 thereof is in the path of movement 45 of the trigger element 52 so as to prevent rearward movement thereof, thus providing a safety device for preventing accidental rearward movement of the trigger element.

A small plate 75 is slidably carried at the upper 50 portion of the housing 50 and has an opening 76 therein through which extends the ear portion 58 of the trigger element. With this arrangement it can be seen that the opening 51 in the housing 50 will remain closed at all times, as the 55 plate 75 extends both forwardly and rearwardly of the ear portion 58 thus preventing foreign matter from entering into the receiver of the gun through the slot 61.

In operation the breech mechanism is closed 60 thus feeding a cartridge into the chamber of the barrel. Upon closing of the breech mechanism the lock-actuating member 17 moves the lock to its uppermost locked position, and one of the extensions 33 of the lock, disengages the sears 65 37 from the head of the firing pin. The gun is now in position ready to be fired by pulling the trigger element 52 rearwardly. The position just described is the same as that illustrated in Fig. 1 70 of the drawings.

By pulling on the cable or cord 59 the trigger element 52 is moved rearwardly in the housing 50, which in turn causes the U-shaped member 47 to be pulled rearwardly due to its connection with the trigger element through the rod 56. 75

This pressure has been applied against tension of the coil spring 57. By shifting the U-shaped member 47 rearwardly the pin 46 carried by the opposite side portions of the U-shaped member, 5 is moved to the rear small end of the slot 45 in the extension 44 of the sear 38, which causes the rear end of the sear 38 to be lowered and the forward end of said sear to be raised and thus disengage the catch 41 from the head of the 10 firing pin. The firing pin is thus moved forward by the spring 25 and the cartridge is fired.

By continuing to pull back on the cable or cord 59 the sear 38 is held in raised position, and the other sear 37 will catch the firing pin upon the 15 final closing of the breech mechanism and hold the same in retracted position until one of the extensions 33 of the lock 16 engages said sear 37 and pushes the same upwardly to disengage the catch portion 39 thereof from the head of the 20 firing pin. Thus it can be seen that by continuing to hold the cable or cord in taut position the gun will continue to fire, and as soon as it is desired to stop firing, the cord or cable 59 is released, which will permit the spring 57 to return 25 the U-shaped member to its forward position and the sear 38 to swing downwardly so that the catch 40 thereon catches the head of the firing pin and holds the same in retracted position.

By having the forward face of the firing pin 30 head and the rear faces of the extension members 33 of the lock 16 offset and the offset portions connected by angle portions, it can be seen that the firing pin will be blocked out so that the point thereof will not contact against the primer of a cartridge unless the lock is in its uppermost locked position, and that when the lock is withdrawn and moved downwardly in order to extract a spent cartridge case from the chamber the angle portions 32 and 34 will slightly retract the 35 firing pin against tension of the spring 25 so that the point 23 of said firing pin is withdrawn from the indentation in the primer.

The rollers 30 on the firing pin head will prevent flexing or bending of the firing pin due to 45 the fact the head 28 of the firing pin is engaged at its uppermost portion, and will permit the firing pin to close very rapidly, thus eliminating faulty firing.

Due to the fact that the breech mechanism is 50 reciprocated in the receiver at a very high rate of speed the safety bar 62 has been provided for preventing movement of the trigger element to the rear in case the back plate 19 has been partially or entirely removed. Without this device 55 and the back plate removed and the gun fired, considerable damage would be done to the party firing the gun, as the entire breech mechanism, would be thrown out through the rear end of the receiver.

60 Having thus described our invention, what we claim as new is:

1. A firing arrangement for automatic guns, in combination with a receiver, a bolt mounted in said receiver for sliding movement, and a lock for 65 locking said bolt in closed position; comprising a pair of sears pivotally carried by the receiver; a spring propelled firing pin carried by the bolt; a head on said firing pin positioned rearwardly of the lock; spring means for normally holding said 70 sears in position to engage the head of the firing pin at the final closing of the bolt to hold the firing pin against movement with the bolt; said lock engaging one of said sears to release the same from the firing pin upon movement of said lock to locking position; said sears engaging one side

of said firing pin head; bearing means on the opposite side of the firing pin head from that engaged by said sears for contacting with a surface of the receiver; and manually controlled means for operating the other of said sears to release the same from the firing pin. 5

2. A firing arrangement for automatic guns, in combination with a receiver, a bolt mounted to reciprocate in said receiver, and a lock for said bolt; comprising a spring propelled firing pin 10 carried by the bolt; a pair of sears pivotally carried by the receiver for engaging said firing pin at the final closing of the bolt to hold the same against movement with the bolt; spring means engaging each of said sears independently for 15 normally holding the same in position to engage the firing pin; said lock cooperating with one of said sears to release the same from the firing pin; an extension on the rear end of the other of said sears, having a cam slot therein, the forward 20 end of said cam slot being enlarged; a manually controlled movable member engaging in the cam slot for depressing the extension of said second mentioned sear, and releasing the firing pin from said sear by rearward movement of said manually controlled movable member. 25

3. A firing arrangement for guns, in combination with a receiver, a breech mechanism slidably mounted in the receiver, and a closure member for the opening through which the breech mechanism is passed during assembly; comprising a firing pin for the breech mechanism, a trigger mechanism carried by the receiver for controlling operation of the firing pin, and a movable element held out of the path of movement of said trigger mechanism by said closure member when the same is in closed position. 30

4. A firing arrangement for guns, in combination with a receiver, a breech mechanism slidably mounted in the receiver, and a closure member for the opening through which the breech mechanism is passed during assembly; comprising a firing pin for the breech mechanism, a trigger mechanism carried by the receiver for controlling operation of the firing pin; and a pivoted bar 40 45 yieldably held out of the path of movement of said trigger mechanism by said closure member when the same is in closed position.

5. A firing arrangement for guns, in combination with a receiver, a breech mechanism slidably mounted in the receiver, and a closure member for the opening through which the breech mechanism is passed during assembly; comprising a firing pin for the breech mechanism, a trigger mechanism carried by the receiver for controlling operation of the firing pin; and a bar pivotally carried by the receiver with one end thereof engaged by the closure member, and the opposite end thereof out of the path of movement of the trigger mechanism, and spring means for 50 55 swinging said bar on its pivot when the closure member is moved from complete closed position to cause the opposite end of said bar to move in the path of movement of the trigger mechanism. 60

6. A firing arrangement for automatic guns, in combination with a receiver, a bolt mounted to reciprocate in said receiver, and a lock carried by said bolt for locking the bolt in closed position; comprising a spring propelled firing pin carried by said bolt; a head on said firing pin and positioned rearwardly of said lock; means for engaging and releasing said head for controlling operation of the firing pin; and a shoulder on said lock cooperating with said head after release thereof by said engaging and releasing 70 75

means for controlling position of said firing pin according to position of the lock.

7. A firing arrangement for automatic guns, in combination with a receiver, a bolt mounted to reciprocate in said receiver, and a lock carried by said bolt for locking the bolt in closed position; comprising a spring propelled firing pin carried by said bolt; a head on said firing pin and positioned rearwardly of said lock; means for engaging and releasing said head for controlling operation of the firing pin; a shoulder on said lock cooperating with said head after release thereof by said engaging and releasing means for controlling position of said firing pin according to position of the lock, and a bearing on said head of said firing pin at the opposite side from that engaged by said shoulder for contacting with a portion of said receiver.

8. A firing arrangement for automatic guns in combination with a receiver, a bolt mounted to reciprocate in said receiver, and a lock carried by said bolt for locking the bolt in closed position; comprising a spring propelled firing pin carried by said bolt; a head on said firing pin positioned rearwardly of said lock; means for engaging and releasing said head to control operation of the firing pin; the adjacent portions of both the lock and firing pin head having offset surfaces connected by angled surfaces thereon which are adapted to mesh when the lock is in complete locked position and the firing pin head released.

9. A firing arrangement for automatic guns, in combination with a receiver, a bolt mounted to reciprocate in said receiver, and a lock carried by said bolt for locking the bolt in closed position; comprising a spring propelled firing pin carried by said bolt; a head on said firing pin positioned rearwardly of said lock; means for engaging and releasing said head to control operation of the firing pin; the adjacent surfaces of the lock and firing pin head having offset surfaces thereon which are adapted to mesh when the lock is in complete locked position and the firing pin head released; and angled cam surfaces arranged at

the offset surfaces of said lock and firing pin head for camming said firing pin rearwardly upon retracting of the lock.

10. A firing arrangement for automatic guns, in combination with a receiver, a bolt mounted to reciprocate in said receiver, and a lock carried by said bolt for locking the bolt in closed position; comprising a spring propelled firing pin carried by said bolt; a head on said firing pin positioned rearwardly of said lock; means for engaging and releasing said head to control operation of the firing pin; the adjacent surfaces of the lock and firing pin head having offset surfaces thereon which are adapted to mesh when the lock is in complete locked position and the firing pin head released; angled cam surfaces arranged at the offset surfaces of said lock and firing pin head for camming said firing pin rearwardly upon retracting of the lock, and a bearing on said firing pin head contacting with a portion of said receiver and arranged on the head at a point opposite to the cam surface on said head.

11. A firing pin arrangement for automatic guns, in combination with a receiver, a movable breech-bolt in said receiver, and a laterally movable lock for said bolt; said breech bolt comprising a firing pin; a head on said firing pin; and co-acting cam surfaces arranged on said lock and firing pin head for retracting said firing pin upon movement of said lock to unlock said bolt.

12. A firing pin arrangement for automatic guns, in combination with a receiver, a movable breech-bolt in said receiver, and a laterally movable lock for said bolt; said breech bolt comprising a firing pin; a head on said firing pin; co-acting cam surfaces arranged on said lock and firing pin head for retracting said firing pin upon movement of said lock to unlock said bolt; and a bearing on said firing pin head engaging said receiver and supporting said head during said retracting of said firing pin.
